Edward J. Stephens

United States Patent Office.

EDWARD J. STEPHENS, OF NORTH PROVIDENCE, RHODE ISLAND.

Letters Patent No. 82,889, dated October 6, 1868.

IMPROVEMENT IN MACHINERY FOR PRINTING YARN.

The Schedule referred to in these Letters Patent and making part of the same.

TO ALL WHOM IT MAY CONCERN:

Be it known that I, EDWARD J. STEPHENS, of North Providence, in the county of Providence, in the State of Rhode Island, have invented an "Improved Method of Printing Yarn;" and I do hereby declare that the following is a full and exact description thereof, reference being had to the accompanying drawing, and to the letters of reference marked thereon.

The nature of my invention consists in providing a method by which yarn passing between two fluted or ribbed rollers is printed with a variety of distinct colors, separated from each other by intervening spaces.

To enable others skilled in the art to make and use my invention, I will describe its construction and operation.

I construct underneath each of said fluted or ribbed rollers as many color-boxes as I want colors on the yarn, each with a color-roller revolving in it, and between each color-roller and the fluted or ribbed rollers that print the yarn, a color-carrier, with flutes or ribs on it, which come first in contact with the color-roller, and then, with the ribbed or fluted rollers, printing the yarn. Said color-carriers are moved by means of gears attached to the shaft of the colors printing the yarn. The color-rollers are moved by means of a belt or gears connected with the color-carriers.

The different parts of my invention are shown on the accompanying drawing, thus:

A A are the fluted or ribbed rollers that print the yarn b with the same color on both sides at the same time as it is made to pass between them.

C C represent the color-boxes.

E E, the color rollers.

F F, the color-carriers.

a a', the gears or cog-wheels.

What I claim as my invention, and desire to secure by Letters Patent, is—

The contrivance and arrangement of the color-carriers F F, as shown in the drawings, and their combination with the color-rollers E E, and the fluted or ribbed rollers A A, so as to put different colors upon different flutes or ribs of the rollers A A, and thus to print the yarn with different colors, with distinct intervals or spaces between.

EDWARD J. STEPHENS.
